UNITED STATES PATENT OFFICE

JOHN G. McCLURG, OF OAK PARK, ILLINOIS

TIE PLATE

Application filed December 17, 1930. Serial No. 502,924.

My invention has for its object the provision in tie plates of a construction adapting the same for use singly or in pairs in connection with railway turnouts, switches, frogs, sidings, guard rails and in such other situations as entail the disposition of the rail members at varying distances apart and at varying angles to the underlying ties.

Heretofore, in track construction at and adjacent switches and the like, it has been the practice to cut-and-fit the successive tie plates, punching the spike holes at progressively varying locations to accord with the edges of the bases of the diverging or converging rails; and where it is undertaken by the mill to provide tie plates ready for use, hundreds of different plates are required to be furnished and selection made on the job of the individual plates suited to each successive tie and rail bearing.

It has been proposed to provide a shoulder as a thrust bearing for the outside of a rail to take the side load off the spikes but where, as in the situation herein referred to, closely adjacent rails have an oblique relation to each other, a thrust shoulder for each rail cannot be provided on the tie plate without providing an almost endless combination because of the varying distances between the shoulders.

Ordinarily the tie plate approximates the width of the tie for distribution of the load over as wide an area as is possible, and it is only when the rails are separated sufficiently to permit of individual tie plates being disposed end to end that such shouldered tie plates can be used. It has been proposed to employ half width plates side by side in lapped relation, each provided with a shoulder at right angles to the length of the plate and tie, the shoulder of each plate being against the gauge side of its particular rail; but where the rails are diverging or converging, the ties and the plates necessarily occupy positions oblique to the rails and at varying angles to the two rails, so that the bearing of the rail on the shoulder is itself oblique; or the companion tie plates must occupy positions out of parallel to each other and to the

tie—an obvious disadvantage in either alternative.

According to my invention, each tie plate is approximately one-half the tie width and is provided, preferably near one end, with an integral shoulder substantially arcuate in form, presenting to the outside of the rail a convex bearing face, so that the bearing against the rail is the same whether the tie and the plate be disposed at a right angle or at an oblique angle to the rail; the plates being, in the case of contiguous rails, ordinarily used in pairs, parallel to each other and to the tie, and each presenting a convex thrust-sustaining shoulder to its particular rail; whereby the one design of tie plate may be used equally well in connection with progressively varying angles of tie and rail and varying distances apart of the rails.

While ordinarily the thrust is away from the gauge side of the rail, yet in some situations as with frogs and guard rails it is desirable to support the thrust by a shouldered portion of the tie plate on the gauge side, and it is found to be advantageous though not absolutely necessary to provide another plate design with a shoulder nearer the center of its length.

In order that the invention and its applicability to track construction in the circumstances above referred to may be readily understood by those skilled in this art, an embodiment of the invention in connection with track construction is set forth by way of example in the accompanying description, defined in the claims and illustrated in the accompanying drawings, wherein

Fig. 1 illustrates in top plan tie plates of my invention as employed in connection with a turnout or siding;

Fig. 2 is a similar view applicable to a frog and guard rail;

Fig. 3 is a detail longitudinal section through one of the tie plates and its underlying tie and transverse section through the overlying rails, taken on the line 3-3 of Fig. 1;

Fig. 4 is a similar detail section taken on the line 4-4 of Fig. 1;

Fig. 5 is a top plan of one design of tie plate; and

Fig. 6 is a top plan of a modified design of plate.

Having reference to Fig. 1 of the drawing, the main rail 11 and the turnout rail 12, occupying the divergent relation to each other, are supported by the ties 13 upon interposed tie plates 14 and 15, the details of which plates 14 and 15 will be hereinafter referred to with more particularity.

In Fig. 2 the relative positions of the ties 13 and the plates 14 and 15 are illustrated in connection with the guard rail 16 and the frog 17.

From both Figs. 1 and 2 it will be observed that due to the diverging relationship of the adjacent rails, the ties are necessarily disposed at oblique angles to either one or both 20 of the rails, while the tie plates, being disposed parallel to the ties, also occupy positions at angles varying in greater or less degree from normal to the rails.

Each of the tie plate designs 14 and 15 is approximately one-half the tie width so that when disposed in lapped relation they jointly distribute the load of the rail over the upper face of the tie. Each design of tie plate has a spike-receiving aperture 18 adjacent one end thereof and each has beyond the median line from the spike aperture 18 a second spike aperture 19 which is elongated in the direction of the length of the plate. Each design of plate also carries an integral shoulder 20 of generally arcuate form, the convex face 21 of the shoulder facing the elongated spike aperture 19 and spaced therefrom a distance corresponding to the width of a rail base 22, the spike aperture 19 being elongated in order to adapt the plate to employment with rails having bases of different width. The tie plate is also provided with spike apertures 23 which advantageously cut the concave portion of the thrust shoulder 20.

The tie plate designs illustrated in Figs. 5 and 6 respectively differ from each other only in that the positions of the thrust shoulder and elongated spike aperture 19 are reversed; that is to say in the design illustrated in Fig. 5 the shoulder is adjacent the end of the plate and the aperture 19 in a medial position, whereas in that design illustrated in Fig. 6 the elongated spike aperture 19 is at the end of the plate and the thrust shoulder 20 occupies a medial position. They are essentially the same in that the convex bearing face of the thrust shoulder is opposed to the elongated slot and spaced therefrom a distance including a range corresponding to the widths of rail bases.

By reference particularly to Figs. 1 and 2 of the drawing the manner in which these tie plates are used is apparent. The convex face of the shoulder bears against that edge

of the rail base opposed to the thrust of a moving wheel. Whether a pair of plates of identical design be employed side by side or a pair of plates of dissimilar design be employed depends altogether upon the contiguous relation of the diverging rails. If the rails be close together as at the two ties at the left side of Fig. 1, identical plates may be employed. Where the relative positions of the two rails are as indicated in the remainder of Fig. 1, it is found preferably to employ dissimilar plates, one of the design shown in Fig. 5 and one of that shown in Fig. 6.

By my invention I render it practicable to support the rails of switches, frogs, turnouts, and the like in oblique relation to each other upon cross ties obliquely arranged relative to one or more of the rails by means of tie plates substantially of one design, presenting an integral thrust support, thus avoiding the trouble and confusion due to the necessary employment of a large number of tie plate designs as has heretofore been required; also, as distinguished from the employment of tie plates having integral shoulders presenting a bearing face not always parallel to the rail, the invention provides an arcuate face which always bears uniformly against the rail even though the angular relation between the tie, the tie plate, and the rail varies. Furthermore, the employment of the integral shoulder as a thrust support distributes the thrust between the several spikes at 18 and 23 rather than requiring the spike 23 to sustain all the thrust.

Additionally, I may employ on the under face of the tie plates ribs or spurs 24 which find a seat in the body of the tie 13 and assist the spikes in resisting the tendency of the tie plate to move longitudinally under the side thrust of the car wheels.

I claim:—

1. An elongated railway tie plate having spike-receiving apertures and a shoulder carried by the plate and arranged to present a bearing face opposed to thrust in directions both in line with and oblique to the major axis of the plate.

2. An elongated railway tie plate having spike-receiving apertures and an integral shoulder spaced from an adjacent aperture longitudinally of the plate a distance corresponding to the width of a rail base, the shoulder arranged to present towards the adjacent aperture a bearing face opposed to thrust in directions both in line with and oblique to the major axis of the plate.

3. An elongated railway tie plate having a plurality of spike-receiving apertures, one aperture being elongated lengthwise of the plate, and a shoulder carried upon the plate and spaced apart from the adjacent elongated aperture a distance corresponding to the width of a rail base, the shoulder arranged

to present towards the adjacent aperture a bearing face opposed to thrust in directions both in line with and oblique to the major axis of the plate.

5 4. An elongated railway tie plate having a plurality of spike-receiving apertures and a shoulder having a convex bearing face disposed towards the adjacent aperture and separated therefrom a distance corresponding to the width of a rail base.

10 5. An elongated railway tie plate having a plurality of spike-receiving apertures, one of said apertures being elongated lengthwise of the plate, and an arcuate thrust-sustaining shoulder having its convex bearing face disposed towards the elongated spike-receiving aperture and separated therefrom a distance corresponding to the width of a rail base.

15 6. An elongated railway tie plate having a pair of spike-receiving apertures, one being elongated lengthwise of the plate, and an integral thrust-sustaining shoulder having a convex bearing face disposed towards the elongated spike aperture and separated therefrom a distance corresponding to the width of a rail base, the plate being provided with an additional spike-receiving aperture substantially at the center of the shoulder.

20 7. In railway track construction, the combination with rails disposed at a relative inclination, and underlying ties disposed at an oblique angle to one of both of said rails, of a plurality of tie plates interposed on a tie beneath both rails side by side in lapped relation, each plate having a generally arcuate thrust-sustaining shoulder with a convex bearing face disposed against the base of one of the rails, and a spike-receiving aperture so positioned relative to the shoulder that a spike therein will bear against the rail base opposite the shoulder.

25 8. In railway track construction, the combination with rails disposed at a relatively progressively varying inclination, and underlying ties disposed at an oblique angle to one or both of said rails, of a plurality of tie plates interposed on a tie beneath both rails side by side in lapped relation, each plate having a generally arcuate integral thrust-sustaining shoulder with a convex bearing face disposed against the base of one of the rails, and a plurality of spike-receiving apertures, one of the apertures being elongated and so positioned relative to the shoulder that a spike therein will bear against the rail base opposite the shoulder.

30 In testimony whereof I have hereunto subscribed my name.

JOHN G. McCLURG.
